UNITED STATES PATENT OFFICE.

MARTIN RASMUSSEN, OF RACINE, WISCONSIN, ASSIGNOR TO GOLD MEDAL CAMP FURNITURE MANUFACTURING COMPANY, OF RACINE, WISCONSIN, A CORPORATION OF WISCONSIN.

COLLAPSIBLE DOUBLE COT.

1,258,243.

Specification of Letters Patent. Patented Mar. 5, 1918.

Application filed June 17, 1916. Serial No. 104,150.

To all whom it may concern:

Be it known that I, MARTIN RASMUSSEN, a subject of the King of Denmark, residing at Racine, in the county of Racine and State of Wisconsin, have invented certain new and useful Improvements in Collapsible Double Cots, of which the following is a specification, reference being had to the accompanying drawing, forming a part thereof.

10 This invention relates to collapsible cots, and the objects of the invention are to provide a collapsible cot on which two people can rest comfortably and which can be folded compactly so as to occupy but little 15 space, for the purposes of transportation or storage.

Referring to the drawings which accompany this specification and form a part hereof, which drawings illustrate an embodiment of this invention, and on which drawings the same reference characters are used to designate the same parts wherever they may appear in each of the several views, Figure 1 is a plan view of the cot set up for use, a part of the canvas covering being shown broken away; Fig. 2 is a side elevation of the cot set up for use; Fig. 3 is an end elevation of the cot set up for use with the stretcher bar removed; Fig. 4 is a side 25 elevation of the cot partly collapsed, the top cover not being shown; Fig. 5 is an end elevation of the frame of the cot in the collapsed position shown by Fig. 4; Fig. 6 is a plan view of the cot frame collapsed, the 30 top cover not being shown; and Fig. 7 is an end elevation, on an enlarged scale, of the frame of the cot in its collapsed condition, as shown by Fig. 6 of the drawings, the view being taken looking in the direction of the 35 arrow on Fig. 6.

Referring to the drawings, the reference numerals 1, 2 and 3 designate supporting trestles or horses each of which are composed of four legs. These legs are designated by the reference numerals 4, 5, 6, 7, 8, 9, 10, 11, 12, 13, 14 and 15, and are pivoted together in pairs by pivots 16, so that they can be collapsed into parallel positions or can be opened into the form of the letter X. 40 Referring to Fig. 3 of the drawings, it will be noticed that the lower ends of the legs 4 and 6 are cut off or beveled at angles, so that the ends of these legs will abut when the legs have been opened to the proper

angle for setting up the cot, and the lower 55 ends of these legs are united by the hinge members 17 and 18, which are secured to the legs and which are connected by the hinge pin 19. The upper ends of the legs 5 and 7 are united by similar hinge members 60 17 and 18, which are hinged together by the hinge pin 19, and the only difference between the construction at the tops of legs 5 and 7 and at the bottoms of legs 4 and 6 is that the tops of legs 5 and 7 are cut off 65 between the hinge members 17 and 18 to receive a center bar 20, which extends lengthwise of the cot for a purpose to be hereinafter explained. The upper ends of the legs 5 and 7 are cut off or beveled at an 70 angle so that the upper ends of these legs will abut against the center bar 20, as clearly shown by Fig. 3 of the drawings.

The construction of the other two trestles or horses and the legs of which they are 75 composed, is the same as to the features of construction already described in connection with the legs 4, 5, 6 and 7.

The cot is provided with side bars 21 and 22, which are composed of two sections 23 and 24 and 25 and 26 respectively. These sections are hinged together by T-shaped plates on opposite sides thereof, only some of which are shown, and which will be referred to as hinges and designated by the 80 reference numerals 27 and 28. Rivets 29 and 30, passing through the hinge 27 and the sections 23 and 24 of the side bar 21, connect these sections of the side bar with the hinge, and rivets 31 and 32 passing 85 through the hinge 28 and the sections 25 and 26 of the side bar 22, connect these sections of this side bar to the hinge 28. The hinges 27 and 28 are secured immovably to the tops of the legs 9 and 11 by rivets or other suitable fastening means, and the ends of the sections 23 and 24 of the side bar 21 are adapted to lie against the upper end of the leg 9, and the ends of sections 25 and 26 of the side bar 22 are adapted to lie against 90 the upper end of the leg 11, as clearly illustrated by the drawings, the construction in this respect forming a kind of rule joint, so that the sections 23 and 24 of the side bar 21 can be collapsed or folded parallel with 95 the leg 9, but can only be opened to positions at right angles therewith, and in a similar manner the sections 25 and 26 of the side

bar 22 can be collapsed or folded parallel with the leg 11, but can be opened only at right angles therewith. The rivets 30 and 32 are located a sufficient distance from the 5 legs 9 and 11, so that the sections 24 and 26 can be collapsed or folded parallel with the legs 9 and 11, and not occupy too much space. The rivets 29 and 31 are located about twice the distance from the legs 9 10 and 11 that the rivets 30 and 32 are, because the leg 8 folds between the section 23 of the side bar 21 and the leg 9, and the leg 10 folds between the section 25 of the side bar 22 and the leg 11, as will be readily understood. Hinge members 33, 34, 35 and 36 connect the top of leg 4 with section 23 of side bar 21, and the top of leg 13 with section 24 of side bar 21, and the top of leg 6 with section 25 of side bar 22, and the top 20 of leg 15 with section 26 of side bar 22, and these hinge members are composed of plates rigidly fastened on opposite sides of the legs and extending at right angles from the legs and connected with the sections of the side 25 bars by single hinge pins 37, 38, 39 and 40.

A canvas cover 41, is secured to the sections 23, 24, 25 and 26 of the side bars 21 and 22, preferably in a permanent manner by tacks, and is provided at its ends with 30 hems 42 and 43, to receive stretcher bars 44 and 45. These stretcher bars are each formed in two parts hinged together so that they can be folded up, the general scheme of the cot being clearly disclosed by Fig. 1 35 of the drawings, and consisting in dividing the cot into approximately four equal sections. Pieces of suitable material 46 and 47, may be secured to one end of the canvas cover 41, to form pillow pockets, and the 40 canvas cover is cut away at the corners and at the hinges 27 and 28 and midway of the hems 42 and 43, to provide clearance so that the cot can be collapsed into smaller compass. The canvas cover 41 is provided with 45 pieces of canvas 48 and 49, secured to the bottom thereof, to form pockets to receive the center bar 20, which also lies between the upper ends of the legs 5 and 7, 8 and 10 and 12 and 14, resting upon parts of the 50 hinge members 17 and 18 uniting the tops of said legs. The center bar 20 is made in two sections connected by a hinge member 50 in the center.

The drawings illustrate the stretcher bars 55 55 as provided with holes to receive dowels formed on the ends of the sections of the side bars 21 and 22 and the center bar 20, so that the stretcher bars will hold the side bars and the center bar in proper 60 spaced relations.

When two persons attempt to occupy a cot, the cover sags and both persons roll to the center of the cot and are uncomfortable. In the cot thus far described however, such 65 action is impossible, because of the pres-

ence of the center bar 20. The pieces of canvas 48 and 49 which form pockets under the canvas top for the center bar 20, anchor the canvas top to the center bar, so that if a heavy person occupies one side of the cot 70 and a light person the other, the canvas does not sag down unduly on the heavy person's side and lift up unduly on the light person's side, as would be the case if the canvas were not anchored to the 75 center bar.

The cot is collapsed or folded in the following manner:

The stretcher bars 44 and 45 are first freed from the dowels on the side bars and 80 center bar, and are then removed from the hems 42 and 43, and can then be collapsed or folded. The center bar 20 is then lifted and withdrawn from the pockets formed by the pieces of canvas 48 and 49, and can 85 then be collapsed or folded. The side bars 21 and 22 are now brought together, which results in collapsing the several legs into the positions shown by Figs. 4 and 5 of the drawings. 90

Referring now to Figs. 4 and 6 of the drawings, the supporting trestle or horse 1, is swung to the left up over and down on to the sections 23 and 25 of the side bars 21 and 22. The supporting trestle or horse 95 3 is swung to the right up over and down against the sections 24 and 26 of the side bars 21 and 22, and then this trestle and the sections of the side bars are swung down parallel with the supporting trestle 100 2, and the motion to the left being continued, the trestle 2 is folded up under the sections 23 and 25 of the side bars with the sections 24 and 26 of the side bars next underneath, and with the supporting trestle 105 3 underneath all, as shown by Fig. 6.

What is claimed is:

1. In a collapsible double cot, the combination of a plurality of trestles, each trestle being composed of legs pivoted together 110 in pairs midway of their lengths, side bars, each of which is composed of sections hinged together so that the sections can be collapsed or folded parallel with each other, one leg of each pair of legs being hinged 115 together at one end and their other ends being hinged to the side bars so that they can be collapsed or folded parallel therewith, the other legs of each pair of legs being hinged together at their upper ends, 120 a center bar adapted to be supported by the legs which are hinged together at their upper ends, stretcher bars adapted to maintain said side bars and said center bar in proper spaced relations, and a flexible cover secured to 125 said side bars and anchored to said center bar.

2. In a collapsible double cot, the combination of a plurality of trestles, each trestle being composed of legs pivoted together in 130

pairs midway of their lengths, side bars, each of which is composed of sections hinged together so that the sections can be collapsed or folded parallel with each other, 5 one leg of each pair of legs being hinged together at one end and their other ends being hinged to the side bars so that they can be collapsed or folded parallel therewith, the other legs of each pair of legs 10 being hinged together at their upper ends with a space between said ends, a center bar composed of sections hinged together so that the sections can be collapsed or folded parallel with each other, and adapted to be inserted in the spaces between the 15 legs which are hinged together at their upper ends, means adapted to maintain the side bars and the center bar in proper spaced relations, and a flexible cover secured to the side bars and provided with 20 means to anchor it to the center bar.

In witness whereof I hereto affix my signature.

MARTIN RASMUSSEN.
